(57) **CLAIM**

The ornamental design for a fire control housing, as shown and described.

DESCRIPTION

FIG. 1 is a rear angled isometric view of the fire control housing;

FIG. 2 is a left side view of the fire control housing;

FIG. 3 is a right side view of the fire control housing;

FIG. 4 is a front view of the fire control housing;

FIG. 5 is a back view of the fire control housing;

FIG. 6 is a top view of the fire control housing; and,

FIG. 7 is a bottom view of the fire control housing.

Broken lines in the Figures show boundaries or environmental structure. The broken lines are not part of the claimed design.
